UNITED STATES PATENT OFFICE.

PERCY RUSSELL, OF SWARTHMORE, PENNSYLVANIA, ADOLPH W. SCHRAMM, OF RIVERTON, NEW JERSEY, AND ROBERT S. WOODWARD, JR., OF HAVERFORD, PENNSYLVANIA, ASSIGNORS TO ELECTRO DENTAL MANUFACTURING COMPANY, OF PHILADELPHIA, PENNSYLVANIA, A CORPORATION OF PENNSYLVANIA.

DESIGN FOR A PEDESTAL FOR DENTAL IMPLEMENTS.

59,932.

Specification for Design.

Patented Dec. 6, 1921.

Application filed October 29, 1920. Serial No. 420,557. Term of patent 7 years.

To all whom it may concern:

Be it known that we, PERCY RUSSELL, ADOLPH W. SCHRAMM, and ROBERT S. Woodward, Jr., citizens of the United States, residing in Swarthmore, Delaware county, Pennsylvania, Riverton, Burlington county, New Jersey, and Haverford, Montgomery county, Pennsylvania, respectively, have invented a certain new, original, and ornamental Design for a Pedestal for Dental Implements, of which the following is a specification, reference being had to the ac-

companying drawings, forming part thereof, in which the figure is a perspective view of the pedestal for dental implements forming the subject of our new, original, and ornamental design.

We claim:

The ornamental design for a pedestal for dental implements, substantially as shown.

PERCY RUSSELL.
ADOLPH W. SCHRAMM.
ROBERT S. WOODWARD, JR.
